[57] CLAIM

The ornamental design for a electrical cigarette, as shown and described.

DESCRIPTION

FIG. 1 is a top plan view of a first embodiment of an electrical cigarette showing our new design;
FIG. 2 is a front elevational view thereof, the back elevational view being a mirror image thereof;
FIG. 3 is a left side elevational view thereof;
FIG. 4 is a right side elevational view thereof;
FIG. 5 is a bottom plan view thereof;
FIG. 6 is a top plan view of a second embodiment of a electrical cigarette showing our new design;
FIG. 7 is a front elevational view thereof, the back elevational view being a mirror image thereof;
FIG. 8 is a left side elevational view thereof;
FIG. 9 is a right side elevational view thereof; and,
FIG. 10 is a bottom plan view thereof.

FIG. 1***FIG. 3******FIG. 2******FIG. 4******FIG. 5*****FIG. 6****FIG. 8****FIG. 7****FIG. 9****FIG. 10**
